[57] CLAIM

The ornamental design for a carrying case for sunglasses or the like, substantially as shown and described.

DESCRIPTION

FIG. 1 is a front elevational view of a carrying case for sunglasses or the like showing our new design;

FIG. 2 is a top plan view thereof;

FIG. 3 is a right end elevational view thereof;

FIG. 4 is a bottom plan view thereof; and

FIG. 5 is a perspective view thereof.

The side not shown has substantially the same appearance as the side shown.

The rear view not shown has substantially the same appearance as the front, minus the decorative plaque.

FIG. 2

FIG. 1

FIG. 3

FIG. 4

FIG. 5
